UNITED STATES PATENT OFFICE

FREDERICK L. SEITZ, OF GARY, INDIANA

DRILLING AND REAMING DEVICE

Application filed July 31, 1930. Serial No. 472,088.

This invention relates to drilling and reaming devices and has for its principal object to generally improve and render more flexible devices of this class, particularly when used in the drilling and reaming of structural steel.

The novel features and advantages of the improved device will be rendered apparent in view of the following description taken in conjunction with the drawings, wherein:

Figure 1 is a plan of a drilling and reaming device and carriage therefor constructed in accordance with the features of the invention.

Figures 2 and 3 are, respectively, views in side and end elevation thereof.

Figures 4 and 5 are fragmentary views in elevation of the drill or reamer and sundry parts, shown removed from the carriage.

Figure 6 is a diagrammatic illustration, showing the flexibility of operation of the device.

Figures 7 and 7^a are detail views in elevation and plan of a modified type of post or support for the device.

A feature which contributes to the flexibility of the improved device is the method of mounting the driving unit whereby the bit, when used for reaming piled or grouped structural shapes, for example, will automatically find its own axis through a series of subdrilled or subpunched holes and produce a true hole the axis of which is the mean of the centers of all the holes subjected to the reaming operation thus compensating for errors in the initial alinement of the holes, or, at the will of the operator, the device will ream at any desired angle within its capacity. Likewise, in drilling, the device will normally drill parallel to its supporting post, but may be readily manipulated to drill at practically any desired angle.

The driving unit is mounted on a carriage which in turn is supported by a post, and the latter may be either clamped to a convenient support or positioned on the work, as will hereinafter appear.

The reference numeral 5 designates the driving unit which is herein shown as an electric or pneumatic drill motor, said motor be-

ing mounted to swing laterally in a yoke 6 by means of trunnion plates 7, which are secured to the motor housing, and have bearing in said yoke and are threaded into said plates, the ends of the yoke being connected and held rigid by means of an end piece 9. The yoke 6 is swingably mounted in a hanger bracket 10 and is held in place by means of hexagonally headed and threaded pins 12.

By means of this type of mounting, the motor or driving unit is permitted to have a universal movement, the yoke 6 and hanger bracket 10 providing a true universal joint assembly.

The foregoing assembly and driving unit are mounted in a lever frame 13 by means of the pins 12, which extend through said frame and hanger 10 and are threaded into the yoke 6, said frame having a control handle 14 secured to the one extremity thereof.

The universal joint assembly and the unit supported thereby as just described are normally held parallel with a supporting post 15 by means of a hook bolt and spring assembly and parallelogram assembly, the first-named assembly comprising a hook bolt 16, cap 17, spring 18, sleeve 19, spring cover 20 and slide hook 21, the cap 17 being formed with a dove-tail groove and is secured to the top of the motor housing, the slide hook 21 being adjustably anchored in said groove. The hook bolt 16 receives the sleeve 19 and spring 18 and is passed through the top of the hanger bracket 10 and engages the slide hook 21.

The parallelogram assembly comprises the hanger 10, above described, link 22, spring 23, bracket 24 and track rails or like members 25, the brackets 24 being rigidly secured in upright position to one extremity of said tracks 25 and the link 22 serving as a pivotal connecting member for the brackets 24 and hanger 10. The lever frame 13 is pivotally secured to the one extremity of the track members 25 by means of a pivot pin 26, and the springs 23 are connected at opposite extremities, respectively, to holder 27 which is secured to brackets 28 which are welded or otherwise fastened to the spring brackets 24, 100

and holders 29 which are threaded into the pins 12.

The post 15 has pivotally mounted thereon a carriage 30 formed with sleeve 31 having a working fit on said post. Rollers 32 are rotatably mounted on said carriage and the tracks 25 have movement on said rollers so that the device as a whole may be reciprocated on said carriage and pivotally moved about said post. The tracks 25 are rigidly connected by cross braces 33, diagonal braces 34 and end bolt 35 and sleeve 35a, the latter preventing overrunning of the tracks or track rails on the carriage.

15 The track rails 25 are provided with guide pieces or brackets 36, which serve to guide and steady the lever frame 13 when the device is working at an angle to the post 15 or when the said lever frame 13 is out of alignment with the rails 25.

20 The carriage sleeve has bearing on an annular shoulder 37 formed on the post 15, the latter projecting slightly above the upper end of the sleeve and a key or pin 38 being passed therethrough, to prevent vertical displacement of the sleeve relatively to said post.

25 The post may be adjusted vertically by means of adjustment screw 39, and in conjunction with or in addition to this adjustment, bushings 40 may be placed on top or at the bottom of the sleeve 31.

30 In Fig. 2 the post 15 is shown clamped to the work by means of bracket 41 and screw 42. However, other means may be employed, 35 such as a magnet, as indicated diagrammatically in dotted lines at 43.

35 A convenient type of post particularly adapted for application to a structural shape or beam which has been previously drilled or punched or where there are holes to receive screw bolts, is shown in Figs. 7 and 7a. In this instance the post 15a is provided with a base 44 which is formed with a plurality of holes 45. The base is shown as of triangular 40 shape and is provided with angularly spaced positioning screws 46, on which the base rests, said screws being adjustable and may be locked in adjusted position by nuts 47. The holes 45 are adapted to receive bolts or pins 45 which may be passed through the base and extend into holes formed in the beam or member on which the device is working or in any other convenient or adjacent support.

50 The flexibility of operation of the device 55 will be apparent from the foregoing description and drawings. When conditions are such as to require a position of the device at an angle to its supporting post, then the parts 16, 17, 18, 19 and 21 come into play and permit the device to take any desired position, either automatically or at the will of the operator, to produce holes in perfect alignment. For instance, on curved or other surfaces not ninety degrees to post 15 or 15a, the operator can drill or ream, without making

any adjustments, holes at any required angle up to the capacity of the machine (note the diagrammatic representation in Fig. 6) by simply controlling the position of the axis of the driving unit and bit by manipulation of the control handle 14.

60 The lateral movement caused by the coordinate of the arc generated by raising and lowering of the handle 14, the axis of the machine being held normally parallel to its supporting post by the action of the movable parallelogram construction formed by the parts 22, 24, 10, 23 is compensated for by the track assembly which is movably mounted on the carriage 30, and this movement also governs the range of track travel. The carriage sleeve 31, being pivotally mounted on the post 15, permits the device to swing horizontally in a full circular arc, limited radially only by the track travel on the carriage. The 85 springs 23 balance the weight of the vertically movable parts.

70 The drill or reaming device, having a universal movement, will follow the lines of least resistance, so that when reaming a series of subdrilled or subpunched holes in layers or piled structural shapes, the bit will find its own axis and produce a true hole having an axis which is the mean of the centers of the holes reamed, thus compensating for errors 95 in the alinement of holes in such material.

75 What is claimed as new is:

1. A drill and reaming device comprising a supporting post, a carriage pivotally mounted on said post for swinging movement about the longitudinal axis of said post, track rails 100 mounted for travel on said carriage, a lever frame pivotally connected to said rails for swinging movement at right angles to the swinging movement of said carriage, a hanger bracket pivotally mounted in said lever frame, a yoke pivotally mounted for swinging movement in said hanger bracket in a direction parallel to the longitudinal axis of said lever frame, a driving unit pivotally mounted in said yoke for swinging movement in a direction at right angles to the longitudinal axis of said lever frame, means for normally maintaining said hanger bracket parallel with said supporting post regardless of the 105 position of said lever frame relative to said rails and resilient means for normally biasing said driving unit into parallel position with said hanger bracket.

110 2. A drill and reaming device comprising a supporting post, a carriage pivotally mounted on said post for swinging movement about the longitudinal axis of said post, track rails mounted for travel on said carriage, a lever frame pivotally connected to said rails for 115 swinging movement at right angles to the swinging movement of said carriage, a hanger bracket pivotally mounted in said lever frame, a yoke pivotally mounted for swing- 120 ing movement in a direction at right angles to the longitudinal axis of said lever frame, means for normally maintaining said hanger bracket parallel with said supporting post regardless of the 125 position of said lever frame relative to said rails and resilient means for normally biasing said driving unit into parallel position with said hanger bracket.

130

ing movement in said hanger bracket in a direction parallel to the longitudinal axis of said lever frame, a driving unit pivotally mounted in said yoke for swinging movement in a direction at right angles to the longitudinal axis of said lever frame, means for normally maintaining said hanger bracket parallel with said supporting post regardless of the position of said lever frame relative to said rails and means for normally biasing said driving unit parallel with said hanger bracket, said means comprising a hook bolt and spring assembly forming a connection between the upper end of said driving unit and said hanger bracket, and a parallelogram assembly including brackets rigidly connected to said track and links connecting said brackets and said hanger bracket.

3. In a drill and reaming device, a pair of track rails, a lever frame pivotally mounted on said rails for vertical swinging movement, an inverted U-shaped hanger bracket pivotally mounted in said lever frame for swinging movement about a horizontal axis, a yoke pivotally mounted in said hanger bracket for swinging movement about a horizontal axis in a direction parallel to the longitudinal axis of said lever frame, a driving unit pivotally mounted in said yoke for swinging movement in a direction at right angles to the longitudinal axis of said lever frame, a spring having a connection with the upper end of said driving unit and said hanger brackets for normally biasing said driving unit into parallel position with said hanger bracket and a parallelogram assembly including said hanger bracket for maintaining said hanger bracket in vertical position regardless of the position of said lever frame relative to said rails.

40 In testimony whereof, I have hereunto set my hand.

FREDERICK L. SEITZ.
